UNITED STATES PATENT OFFICE

WILLIAM J. O'NEILL, OF RIVER FOREST, ILLINOIS, ASSIGNOR TO MERCIL PLATING EQUIPMENT COMPANY, OF CHICAGO, ILLINOIS, A CORPORATION OF ILLINOIS

CLAMP

Application filed March 15, 1930. Serial No. 436,167.

My invention relates to a clamping device which is inclusive of two arms each having a jaw on one end thereof and which are articulated at their other ends. In accordance with one feature of the invention one of the arms is provided with a tongue where it is in articulated connection with the other and the latter arm is there provided with a groove in which said tongue is snugly received. I provide a metallic coupling member within said tongue and the adjacent sides of said groove, the aforesaid arms being made of a non-metallic acid resisting substance which will expand under the influence of liquid to eliminate clearance between said tongue and groove side. In the preferred embodiment of the invention the metallic coupling is formed to force relative movement of said arms toward and away from each other. I provide a handle which is coupled with said coupling and closely against one side of the groove to effect the operation of said coupling, this handle being also made of a non-metallic acid resisting substance which will expand under the influence of liquid to bring the handle closely against the groove side adjacent thereto. The clamping device thus made is of particular service in connection with electro-plating barrels which are to be passed into and out of an electrolyte in a plating operation, clamps of this character having been employed for the purpose of holding closures in place upon plating barrels.

In accordance with another characteristic of the invention the clamping device is inclusive of a coupling which is employed to unite the ends of the arms that are to be articulated. This coupling is formed to relatively move said arms to increase or decrease the spacing between the jaws. In the preferred embodiment of the invention the coupling is in the form of a shaft journaled in said tongue and the sides of said groove, the portion of the shaft journaled in the tongue being eccentric with respect to the portion of the shaft journaled in the sides of the groove.

I will explain my invention more fully by reference to the accompanying drawings in which Fig. 1 is a view illustrating a plating

tank in section and a plating barrel in assembly therewith and shown in elevation; Fig. 2 is a sectional view on line 2—2 of Fig. 3, but omitting the tank; Fig. 3 is an enlargement of a part of the structure shown in Fig. 2 but turned at right angles, contiguous portions of the arms of the illustrated clamping device being shown in section; Fig. 4 is a sectional view on line 4—4 of Fig. 3; and Fig. 5 is a sectional view on line 5—5 of Fig. 3.

I have illustrated a tank 1 in which an electroplating electrolyte 2 is contained. A plating barrel is adapted for partial immersion within the electrolyte and for rotation while partially immersed, as is well known by those familiar with the art. The plating barrel illustrated is inclusive of end walls 3 which carry stub shafts, not shown, that are supported within the bearings 4 which may be lowered or elevated to partially immerse the barrel within and withdraw it from the electrolyte. The barrel is also inclusive of perforated panels 5 through which the electrolyte 2 may have access to the interior of the barrel and the objects within the barrel that are to be electroplated. The barrel is shown as being generally hexagonal, one of the panels 6 being carried by a frame 7 that constitutes, therewith a closure which is removed when the objects to be plated are to be passed into the barrel and, when plated, are to be removed from the barrel. Ribs 8 intervene between the end walls 3 and are held in assembly with the end walls by metallic rods 9 which pass through said ribs and are in fixed connection with the end walls of the barrel. The end walls and ribs of the barrel are made of bakelite or other suitable acid resisting material as are also the panels 5 and 6 and the frame 7 for the latter panel.

The panel 6 and its supporting frame 7 are adapted to be clamped in place by clamping devices of my invention of which two are shown for this purpose. Each clamping device illustrated is inclusive of two arms 10 and 11, each made of acid resisting material such as bakelite. The arm 10 has a tongue 12 formed upon one end thereof and the arm 11 has a groove formed in one end thereof within which and between the sides 13 of

which the tongue is snugly received. The coupling which unites the arms is in the form of a metallic shaft having coaxial portions 14 and 15 journaled within the groove sides 13 and a circular portion 16 journaled within the tongue 12 and eccentric with respect to the other shaft portions. The shaft portion 16 is desirably separately formed from the balance of the shaft structure in which event the portions 14 and 15 are in one piece with the part thereof which passes through the portion 16 polygonal in cross section, whereby the shaft part 16 turns with the balance of the shaft structure. To guard against endwise movement, I form the shaft portion 15 with an annular groove 17 which receives a metallic pin 18 that is carried by a groove side 13 and is received therein through an opening of corresponding size. A handle 19, also made of suitable resisting material such as bakelite, is secured to the shaft portion 15 by means of a metallic pin 20 which is received within an opening formed in the handle and is passed through an opening that is diametrically formed in the shaft portion 15. The contiguous faces of the tongue 12 and groove sides 13 are in intimate contact as are the contiguous faces of the handle 19 and the arms 10 and 11. The intimacy of the contact between these contiguous faces is enhanced by the swelling of the handle and arms under the influence of the acid solution, the handles and arms expanding to eliminate the clearance between the tongue and groove sides and between the handle and the arms, whereby access of the acid to the metallic coupling 14, 15, 16 is guarded against. To further guard the metallic portions of the structure against the access of moisture thereto, I provide a closure plug 21 of bakelite in the outer end of the opening that receives the pin 18; plugs 22 of bakelite in the ends of the opening that contain the pin 20 and plugs 23 of bakelite that cover the ends of the shaft portions 14 and 15. The jaws 24 at the outer ends of the clamping arms are designed to grip the ribs 8 between which the closure 6, 7 is disposed. When the handle 19 is in the position illustrated said jaws are clamped against the ribs by virtue of the fact that the eccentrically related portions of the shaft structure 14, 15, 16 have been adjusted to force the articulated ends of the arms toward each other to effect an approach of said jaws. When the closure 6, 7 is to be removed, said handle is turned half way round which will move the articulated ends of the arms apart to an extent which will move said jaws sufficiently apart to permit their removal from the ribs engaged thereby. When the handles 19 of both clamping devices have been thus adjusted the closure 6, 7, may be removed. The frame 7 is desirably provided with bridge pieces 25 which are disposed beneath the clamping arms 10 and 11. These

bridge pieces are engaged by the extreme ends of the groove sides 13 and the tongue 12 when the handles 19 have been adjusted to engage the jaws 24 with the contiguous ribs 8. The arms of the clamping devices are thus enabled to press the closure 6, 7 into place when the handles have been suitably manipulated.

Changes may be made without departing from the invention.

Having thus described my invention, I claim:

1. A clamping device inclusive of two arms each having a jaw on one end thereof, one arm having a tongue on the other end thereof and the other arm having a groove upon its other end in which said tongue is snugly received; and a metallic coupling member within said tongue and the adjacent sides of said groove, the aforesaid arms being made of a non-metallic acid resisting substance which will expand under the influence of liquid to eliminate clearance between said tongue and groove sides.

2. The structure of claim 1 wherein the metallic coupling is formed to force relative movement of said arms toward and away from each other and a handle is coupled with said coupling and closely against one side of the groove to effect the operation of said coupling, this handle being also made of a non-metallic acid resisting substance which will expand under the influence of liquid to bring the handle closely against the groove side adjacent thereto.

3. A clamping device inclusive of two arms each having a jaw on one end thereof, one arm having a tongue on the other end thereof and the other arm having a groove upon its other end in which said tongue is snugly received; a coupling in the form of a shaft journaled in said tongue and the sides of said groove, the portion of the shaft journaled in the tongue being eccentric with respect to the portion of the shaft journaled in the sides of the groove; and a handle upon said shaft.

4. A clamping device inclusive of two arms each having a jaw on one end thereof, a coupling uniting the other ends of the arms and formed to relatively move said arms to increase or decrease the spacing between the jaws including a shaft having portions journaled in the contiguous ends of said arms, a portion of the coupling journaled in one arm being eccentric with respect to the portion of the coupling journaled in the other arm, and a handle in connection with the coupling for effecting its operation.

In witness whereof, I hereunto subscribe my name.

WILLIAM J. O'NEILL.
